UNITED STATES PATENT OFFICE

HENRY A. GUIGNON, OF CORRY, PENNSYLVANIA.

IMPROVEMENT IN COMBINED LIQUID-PUMPS AND FUNNELS.

Specification forming part of Letters Patent No. 179,911, dated July 18, 1876; application filed June 6, 1876.

To all whom it may concern:

Be it known that I, HENRY A. GUIGNON, of Corry, Erie county, Pennsylvania, have invented a new and Improved Combined Liquid-Pump and Funnel, of which the following is a specification:

The accompanying drawing represents a vertical central section of my improved liquid-pump and funnel combined.

The invention has reference to an improved pump and funnel, by which the liquids may readily be drawn out of the barrel and the waste liquid returned back to the same; and the invention consists of a pump passing through a bung into the barrel, the bung being recessed and connected by a pipe with a funnel and grate for conveying the waste liquid back into the barrel.

In the drawing, A represents a pump of suitable length, with a valve-piston, B, operated by a handle, B', and with a discharging-spout, C. The lower end of pump A is provided with spurs a, by which the pump-barrel rests on the bottom part of the barrel, to prevent the turning of the pump during the working of the piston. The pump A slides in a perforated wooden bung, F, which is surrounded by a tin case, to prevent the jamming or splitting of the bung when being driven firmly into the barrel. The bung F has a recess, b, that connects by an elbow-pipe, E, with a funnel, D, which carries a grate, D¹,

for supporting the measuring-vessels placed thereon. A ring-shaped guide, d, of the funnel serves, in connection with the bung, to adjust the pump to different sizes of barrels, and forms a steady support for the same. A central pipe, D², of the funnel D, with openings e near the bottom, extends below the funnel D, and forms a loose joint with the bung-connecting pipe E, being also extended in upward direction to support the center part of grate D¹. The pump, being attached to the side of funnel, may be readily worked for filling the measure and other vessels in taking samples, and for other purposes, while the liquid not required is readily returned to the barrel by means of the funnel and recessed bung.

The pump may be readily detached from the bung when desired to be used without the funnel for pumping the contents of one barrel into another, and for other purposes.

Having thus described my invention, I claim as new and desire to secure by Letters Patent—

The funnel connected with a recessed bung by an elbow-pipe, E, and with pump by a band, d, to enable it to be supported, as shown and described.

HENRY A. GUIGNON.
